UNITED STATES PATENT OFFICE.

WILLIAM D. WILCOX, OF CHICAGO, ILLINOIS.

APPARATUS FOR MANUFACTURING GAS.

1,332,369.

Specification of Letters Patent.

Patented Mar. 2, 1920.

Application filed April 1, 1918. Serial No. 225,964.

To all whom it may concern:

Be it known that I, WILLIAM D. WILCOX, a citizen of the United States, and a resident of Chicago, in the county of Cook and State of Illinois, have invented certain new and useful Improvements in Apparatus for Manufacturing Gas, of which the following is a specification, reference being had to the accompanying drawings.

10 My invention relates to the manufacture of gas for domestic and other uses, and has for its object to provide a new and improved apparatus for the manufacture of combined coal and water gas suitable for use with bituminous coals which contain only a small proportion of moisture and combined oxygen. I accomplish this object as illustrated in the accompanying drawings and as hereinafter described. What I regard as new is set 20 forth in the claims.

In the drawings:—

Figure 1 is a horizontal sectional view substantially on the line 1—1 of Fig. 3, some parts being in elevation;

25 Fig. 2 is a vertical sectional view on line 2—2 of Fig. 1;

Fig. 3 is a longitudinal vertical section substantially on line 3—3 of Fig. 1, some parts being in elevation;

30 Fig. 4 is a partial vertical cross-section on line 4—4 of Fig. 1, some parts being broken away, and Fig. 5 is a vertical cross-section on line 5—5 of Fig. 1, some parts being broken away.

35 Referring to the drawings, and particularly to Fig. 1, it will be noted that my improved apparatus comprises four rectangular generators A, B, C, and D arranged in the form of a block or square. The generators A—C are spaced a distance apart to accommodate a combustion chamber E, the intermediate portion of which is filled with checker brick. In like manner, the generators B—D are separated by a similar combustion chamber F. Between the generators A—C and the combustion chamber E at one side of the apparatus, and the generators B—D and the combustion chamber F at the other side of the apparatus, is an intermediate longitudinally-extending chamber G which communicates at one end with the flues of a boiler H through a passage 6 which is preferably downwardly inclined, as shown in Fig. 3. At the opposite end of the apparatus from the boiler H is a condenser I which connects through a pipe 7, best

shown in Fig. 3, with a fixing chamber or main J located in the upper portion of the chamber G, as shown in Figs. 1 and 3. This fixing chamber is preferably composed of two connected members 8—9 arranged to form a tortuous passage through which the conserved gases pass from the several generators to the condenser I, as will be hereinafter explained more in detail. 10—11 indicate the side walls of the chamber G. 12 indicates a wall between the generator A and the combustion chamber E; 13 indicates a similar wall between the generator B and the combustion chamber F; 14 indicates a similar wall between the generator C and the combustion chamber E, and 15 indicates a similar wall between the generator D and the combustion chamber F. 16—17 indicate the outer side walls of the apparatus, and 18—19 indicate the end walls thereof. 20 indicates a passage in the upper portion of the wall 12 near the outer wall 16 for admitting gases from the generator A to the outer end of the combustion chamber E; 21 indicates a similar passage in the wall 13 between the generator B and the combustion chamber F; 22 indicates a corresponding passage in the wall 14 between the generator C and the combustion chamber E, and 23 indicates a similar passage in the wall 15 between the generator D and the combustion chamber F. These several passages are provided respectively with gate valves 24, 25, 26 and 27, as shown in Fig. 1, all of which are arranged to be operated from the top of the apparatus by means of operating rods denoted by corresponding numbers with the exponent a . 28 indicates a passage in the lower portion of the wall 12 adjacent to the wall 10 connecting the generator A with the inner lower portion of the combustion chamber E, as indicated by dotted lines in Fig. 1, said passage having a gate valve 29 operated from the top of the apparatus by a rod denoted by the corresponding number with the exponent a . 30 indicates a similar passage between the generator C and the combustion chamber E, said passage having a valve 31. In like manner the generators B and D are connected with the combustion chamber F by passages 32—33, respectively, having valves 34—35, respectively. The passages 30 and 33 are shown in full lines in Fig. 5.

36 indicates a passage connecting the lower inner portion of the combustion chamber E

with the intermediate chamber G, said passage being controlled by a gate valve 37, as shown in Fig. 5, a rod 37^a being provided to operate it. Similarly the combustion chamber F is connected with the intermediate chamber G by a passage 38 having a valve 39 operated by a rod 39^a, as shown in said figure and as indicated by dotted lines in Fig. 1. 40 indicates a passage connecting the lower portions of the generators A—B, said passage extending under the intermediate chamber G, as shown in Fig. 4, and indicated by dotted lines in Fig. 1. Said passage is provided with a valve 41 operated from above by a rod 41^a. 42 indicates a similar passage connecting the generators C—D, the latter passage having a valve 43 operated by a rod 43^a, as shown in Fig. 2.

44 indicates a steam supply pipe having branches 45, 46, 47 and 48 which respectively discharge into the ash-pits of the several generators, each of which is provided with the usual grate 49, as shown in Figs. 1 and 2. These branch pipes 45, 46, 47 and 48 are provided with valves 51, 52, 53 and 54, respectively, so that the steam supply may be controlled. 55 indicates a heated air main which extends from one side of the condenser I around one side of the apparatus, and is provided with branch pipes 56—57 communicating respectively with the ash-pits of the generators A—C and with a branch 58 which communicates with the upper portion of the combustion chamber E, as shown in Fig. 1. These branches are provided respectively with valves 59—60—61. A similar main 62 is provided at the opposite side of the condenser I and extends around the opposite side of the apparatus, being provided with branches 63—64—65 for supplying air to the generators B—D and the combustion chamber F. 66—67—68 indicate valves in said branch pipes. 69 indicates an air supply pipe which communicates with the condenser I, and is provided with a blower, not shown, for directing a current of air through the condenser to the mains 55—62, the arrangement being such that the air passing through the condenser will be heated to a certain extent, and will at the same time cool the gases passing through the condenser. The several valves controlling the air supply pipes are arranged to be operated from the top of the apparatus, as illustrated in Figs. 2, 4 and 5, so that an attendant on top of the apparatus may have ready access to all the several valves.

70 indicates a gas outlet pipe leading from the upper portion of the generator A to a main 71 which delivers the gas to the upper section 8 of the fixing chamber J, as best shown in Fig. 4. 72 indicates a similar pipe which connects the generator B with the main 71, the pipes 70—72 having valves 73—74, respectively. The generators C—D are

similarly connected with a main 75 at the opposite end of the apparatus, the latter main being also connected with the section 8 of the fixing chamber J. 76 indicates hoppers disposed over openings 77 in the roofs of the several generators for supplying fresh fuel thereto. These hoppers may be of any suitable construction for delivering proper charges to the generators at suitable intervals, but they are preferably provided with rotary valves 78, as shown in Fig 2. It will be understood that the several generators are provided with the usual ash removal and clinkering doors, which need not be specifically described. Also the sections 8—9 of the fixing chamber J may be provided with removable ends, as shown at 79—80 in Fig. 3, for cleaning out purposes. 81 indicates an exhaust fan connected with the condenser I, as shown in Fig. 3, for maintaining the flow of the conserved gases from the several generators through the fixing chamber and out through the condenser. The rate of flow of the gases may, of course, be controlled by means of this fan.

The operation is as follows: Prior to beginning the operation of gas making, blasting will be carried on with the several generators only partially filled with fuel until the walls, flues, etc., have become well heated,—after which the two generators at one end of the apparatus, as C—D, will be filled with fresh fuel above the incandescent coke therein. During this preliminary blasting period, the valves in the upper passages 20, 21, 22 and 23 connecting the several generators with their respective combustion chambers will be open, and also the valves in the passages 36—38 connecting the lower portions of said combustion chambers with the intermediate chamber G. At the same time the appropriate valves will be open to supply air below the ash-pits of the several generators and to the upper portions of the combustion chambers E—F. Thus the blast gases will pass from the several generators to the combustion chambers E—F where complete combustion will be promoted by the secondary air admitted through the pipes 58—65, and the waste gases will then pass through the intermediate chamber G to and through the flues of the boiler H, generating steam for use in the gas making process. When the preliminary blasting has been carried on to the point that the apparatus has attained the requisite temperature, and fresh fuel has been supplied, as above indicated, to the generators C—D, the blasting is continued in the generators A—B, but the passages 22 and 23 leading from the upper portions of the generators C—D to the combustion chambers E—F, respectively, are closed, and the gas outlet passages from said generators are opened. At this time also the valves 31, 35, 41 and 43

are all closed. As long as the generators A and B are continued on blast, which depends upon the temperature of the fuel therein, the valves 24 and 25 are left open 5 as well as valves 37 and 39. Assuming that the proper temperature has been attained in the generator B, air is shut off from said generator and also from the combustion chamber F, and steam is admitted to said 10 generator through the pipe 46 to purge said generator and the combustion chamber F of waste gases. At the completion of the purging operation, the valve 39 is closed to cut off the combustion chamber F from the 15 waste gas or intermediate chamber G and the valves 35 and 43 are opened. The steam admitted to the generator B then rises through the mass of incandescent fuel and is converted into water gas which passes 20 upward through the passage 21 into the combustion chamber F where it is superheated by the heat from the checker brick. The gases formed then pass down through the passage 33 into the chamber below the grate 25 of the generator D, a part of the gas also passing across under the intermediate chamber G through the passage 42 to the generator C. These gases rise through the incandescent fuel in the generators C and D 30 and also through the superposed coal in said generators to which they impart heat, boiling out the volatiles contained therein, the resulting mixed gases passing out through the gas outlets at the top of said 35 generators. When the temperature in the fuel body in the generator B is lowered below the point of effective operation for the manufacture of water gas, the operation of manufacturing water gas can be continued 40 with the generator A, in this case the flow of gases being reversed so that they pass first to the generator C and then to the generator D substantially in the manner already described. During this interval, 45 blasting is resumed in the generator B. When the level of the fuel in generators A and B has been lowered by the several periods of blasting and gas generation below the height desirable for efficiency, generators A and B are supplied with fresh 50 fuel. The fuel in the generators C and D has in the meantime been fully carbonized. Generators C and D may now be operated on blast and then on run, as has been described in connection with generators A and B, and, the hot water gas produced used to carbonize the fresh fuel in the upper levels 55 of generators A and B. In other words, the generators at one end of the apparatus, 60 as A and B, are operated in conjunction with generators C and D to supply hot water gas to generators C and D and promote the manufacture of coal gas in the latter generators, and afterward the situation is 65 reversed and the generators C and D are used to supply hot water gas to the generators A and B and promote the distillation of coal gas in the latter generators, all the conservable gases being discharged together into the fixing chamber J. This 70 fixing chamber is highly heated as there is practically a constant flow of hot waste gases through the intermediate or waste gas chamber G, and consequently the lighter condensable vapors carried by the gas will 75 be cracked and turned into fixed gases before the mixed gases pass into the condenser. As the air supply to support the operation of blasting passes through the condenser, not only does it serve to cool the 80 gases, but also the heat of the gases is taken up by the air and restored to the process.

The advantages of the apparatus described lie principally in the fact that there is great economy of heat and an important 85 saving of labor as no manipulation of the fuel is required from the time it is charged in quantity into the generators until the mineral residue is removed as ash. Beyond the limited loss by radiation and in the 90 ashes removed, the sensible heat escaping is largely utilized to produce steam and pre-heat air, both of which reenter the apparatus and are thus conserved. The continuity of the operation when four generators are grouped as described is of substantial advantage as an element of efficiency, since there is a continuous passage 95 of hot gas through the fuel to be coked, a continuous passage of hot gas through the air 100 cooled condenser, a continuous drawing of air through the condenser, serving the double purpose of cooling the gas more rapidly and heating the air, and a continuous supply of hot waste gas to the steam 105 boiler. There is also a continuous supply of conserved gas of very nearly uniform composition and constant volume so that the operation of the accessory purifying apparatus can be carried on with good efficiency. 110

What I claim as my invention, and desire to secure by Letters Patent, is:—

1. An apparatus for manufacturing gas comprising in combination two gas generator chambers, a secondary combustion chamber 115 intermediate between the two generator chambers, means for supplying fuel to and withdrawing ash from each generator chamber, valve controlled means for introducing air to the lower portion of either generator 120 chamber, means for admitting air to the combustion chamber, means for withdrawing the waste gas from the lower portion of the combustion chamber, valve controlled means for passing steam into the lower part of 125 either generator chamber, valve controlled means for passing the gases generated in either generator chamber into the upper part of the combustion chamber, thence into the lower part of the other generator 130

chamber and up through the contents thereof, and means for withdrawing the gases through an outlet in the upper portion of the latter generator chamber.

5. 2. An apparatus for manufacturing gas, comprising in combination, two gas generator chambers, means for introducing fuel into the upper part of each generator chamber, a closable gas outlet in the upper part 10 of each generator chamber, means for removing ashes from the lower part of each generator chamber, valve controlled means for introducing air and steam into the lower part of each generator chamber, a combustion chamber intermediate between the two generator chambers, closable openings from the upper and lower part of each generator chamber into the combustion chamber, a closable opening for the admission of air 15 into the upper part of the combustion chamber, and a closable outlet in the lower part of the combustion chamber for the withdrawal of waste gas.

3. A gas making apparatus comprising

four gas generator chambers, a combustion 25 chamber between and connecting each two of the four generator chambers, an intermediate waste gas chamber, closable openings for the supply of air to the lower part of each generator chamber, means for admitting steam to the lower part of each generator chamber, closable openings connecting the upper and lower part of each generator chamber with the adjacent combustion chamber, a closable opening for the supply of 30 air to the upper part of each combustion chamber, a closable opening from each combustion chamber into the lower part of the waste gas chamber, a closable passage from each generator chamber leading under the 35 waste gas chamber to the adjacent generator chamber, closable gas outlets at the upper part of each generator chamber, means for introducing fuel into the upper part of each generator chamber, and means for removing 40 ash from the lower part of each generator chamber.

WILLIAM D. WILCOX.
